UNITED STATES PATENT OFFICE.

EDWARD A. ROBINSON, OF MONTREAL, QUEBEC, CANADA, ASSIGNOR OF ONE-HALF TO HIMSELF AND ONE-HALF TO ELLISON A. WORKMAN, OF MONTREAL, CANADA.

ADJUSTMENT FOR TERMINALS WITHIN CONNECTER HEADS.

Application filed May 17, 1922. Serial No. 561,706.

To all whom it may concern:

Be it known that I, EDWARD A. ROBINSON, a citizen of the United States, residing at Montreal, Province of Quebec, Canada, have invented a certain new and useful Adjustment for Terminals Within Connecter Heads, of which the following is a specification.

My invention relates to train connecters intended for automatic operation to join air or steam pipes of adjacent cars.

The purpose of my invention is to provide quick, ready and reliable means for determining the extent of normal projection of train pipe terminals beyond the connecter head by which they are carried.

A further purpose is to adjust the total extent of projection of a train pipe terminal by bolts or studs extending parallel to the axes of the train pipe terminals and surrounded individually, or collectively, for each terminal by springs with springs about the terminals inside the bolts in the latter case.

25 Further purposes will appear in the specification and in the claims.

I prefer to illustrate my invention by two slightly variant forms only, selecting forms which are practical, efficient and relatively inexpensive, and which at the same time well illustrate the principles of my invention.

30 Figure 1 is a side elevation of a connecter head and its supporting mechanism to which my invention is applied.

35 Figure 2 is a vertical, longitudinal section through the head—considered as detached from its supports—showing one of the forms of my invention.

40 Figure 3 is a section of Figure 2 taken upon line 3—3.

Figure 4 is a fragmentary longitudinal section showing the other form.

In the drawings similar numerals indicate like parts.

45 In Figure 1 I have shown a head 5 with mounting therefor corresponding generally to that shown in a copending application filed by me September 25, 1920, for connecter for train pipes, Ser. No. 412,647, in which the 50 head is carried by a yoke 6 whose feet 7, 7' are bolted to the head. At the rear the yoke

surrounds the usual bracket 8, being fitted against it from the rear so that the inner transverse surface 9 of the yoke abuts against the rear face 10 upon the bracket. The yoke 55 is forked on opposite sides of the bracket providing guide openings 11 for the bracket pins 12. The yoke is pressed against the rear of the bracket by a spring 13 held to its duty by bolt 14 engaging a pin 15 in the 60 bracket at one end and retained at the rear by a nut and washer construction 16. The usual gathering wings 17 are shown. Obviously the character of head support used 65 does not affect my present invention except as it may co-operate with or interfere with the functioning of the present invention.

Within the head I form somewhat larger 70 openings 18 for the train pipe terminals than in the usual form in order to accommodate the terminal pipes 19, any desired number of bolts or studs 20 by which the projection of the terminals is to be limited and adjusted and springs for pressing the terminals forward. A variety of forms or springs is 75 permissible, consistent with the placing of the bolts or studs and falling generally into the classes of (a) individual to the bolts or studs, and (b), surrounding the terminals.

The terminals pass through bores 21 with 80 in internally extending flanges 22 and are enlarged at their outer ends at 23 to fit counterbores 24. The enlargements afford seats for the gaskets 25, 25', anchorages for the bolts or studs 20 and abutments for the 85 outer ends of spiral springs 26, surrounding the individual bolts in Figures 2 and 3 or 27, 28 surrounding the terminals outside and inside the bolts, respectively in Figure 4.

The springs press at their rear ends 90 against the flanges 22 and the bolts or studs pass through these annular inwardly directed flanges 22 and receive lock nuts 29 which bear against the rear faces of the flanges.

The heads are annularly recessed at 30 to 95 protect the nuts and bolts from accidental interference.

The annular recesses 30 afford access for a socket wrench by which the nuts may be 100 adjusted. The gaskets 25 and 25' are the usual air pipe and steam gaskets, respectively and the steam terminal gaskets are retained

by the spring 31 as usual. Within the terminals I place ribs 32 for engagement by a plug wrench so as to conveniently screw the terminals into the fittings 33, 34 for connections which may be Westinghouse and Gold couplers 35 and 36.

My invention is equally applicable to heads intended to carry but a single terminal, as would more usually be the case in freight service and to heads intended to carry two or three terminals as ordinarily required in passenger service.

In assemblage I will consider separately the conditions if the fittings 33, 34 be free 15 to be rotated for application after the rest of the structure has been assembled and while the terminal is being steadied in its position by a socket wrench.

In that event the studs are first screwed 20 into the enlargements 23 and the springs are put in position within the spaces 18. The terminals, with the studs attached, but without the lock nuts, and with the springs either about the individual studs or about the terminals 25 are put in position so as to pass the studs through the openings in flanges 22. The lock nuts 28 are then set and the fittings are subsequently attached. This is the preferred form of assemblage since the capability 30 of placing the fittings 33, 34 after the head is otherwise assembled, carries with it the capability of disconnection of the fittings from the terminals without disassembly of the rest of the head structure.

Where the fittings are not free to rotate, the springs are inserted within the head openings and the terminals are placed and screwed into the fittings before the studs are placed within the enlargements 23. The 40 studs are first passed through the flanges 22 and through or between the springs and are afterward screwed into the enlargements, after which the nuts 29 are seated by socket or spanner wrench.

In either event the extent of normal projection of the terminal beyond the head may be accurately determined and may subsequently be adjusted with great nicety by seating the lock nuts at appropriate positions 50 upon the studs.

It will be evident that the main reason for placing the flange 22 within the head instead of at the outer edge of the head is to give room for the nuts within the head and 55 to avoid interference with the adjustment and breakage of the threaded stems at the rear of the head protecting also from accidental displacement of these nuts. Where these advantages of protection do not appeal, there is an obvious advantage in placing the flange 22 far enough back for the nuts to be accessible by the use of an ordinary wrench.

Where the springs encircle the studs or 60 bolts more springs are required but there is

some advantage from the increased number of springs, in that any one of them is effective to give partial support and pressure in case of breakage of the others.

It will be obvious that the disclosure of 70 my invention will suggest to those skilled in the art other forms by which all or a part of the benefits of my invention may be secured, and it is my purpose to include herein all such as come within the reasonable spirit 75 and scope of my invention.

Having thus described my invention, what I claim as new and desire to secure by Letters Patent is:—

1. In an automatic train pipe connector, 80 a connector head having an opening therethrough counterbored at the forward end and providing an inwardly extending flange in the rear thereof, a train pipe terminal passing through the opening and enlarged 85 at the forward end to slide within the counterbore, studs secured to said enlargement, and extending through the flange, nuts on the studs affording adjustment of maximum terminal extension and springs about the terminal within the counterbore bearing against the enlargement and flange. 90

2. In an automatic train pipe connector, 95 a connector head having an opening therethrough counterbored at the forward end and providing an inwardly extending flange in the rear thereof, a train pipe terminal passing through said opening and enlarged at the forward end to slide within the counterbore, studs fastened to said enlargement 100 and extending through the flange, nuts on the studs affording adjustment of maximum terminal extension and a spring surrounding the terminal and pressing it forward resiliently. 105

3. In an automatic train pipe connector, 110 a connector head having an opening therethrough counterbored at the forward end and providing an inwardly extending flange in the rear thereof, a train pipe terminal passing through said opening and enlarged 115 at the forward end to slide within the counterbore, studs secured to said enlargement and extending through the flange, nuts on the bolts affording adjustment of maximum terminal extension and springs surrounding the terminal inside and outside of the bolts and pressing the terminal forward resiliently. 115

4. In an automatic train pipe connector, 120 a connector head having a bore therethrough counterbored forwardly and recessed in the rear thereof, in combination with a train pipe terminal slidably fitting within the bore and counterbore, and retaining devices secured to said terminal and passing through the flange between the counterbore and recess into said recess, adjustment therefor within the recess and a spring within the 125 counterbore pressing the terminal forwardly. 130

5. In an automatic train pipe connector, a connector head having a bore and a counterbore, a train pipe terminal through the bore and counterbore fitting to the bore at the rear and forwardly enlarged to slide within the counterbore, bolts engaging the enlargement at one end and limiting the forward projection of the terminal, springs within the counterbore pressing the terminal forwardly and adjusting devices accessible from the rear for determining the extent of projection of the terminals.

EDWARD A. ROBINSON.

Certificate of Correction.

It is hereby certified that the name of the second assignee in Letters Patent No. 1,509,814, granted September 30, 1924, upon the application of Edward A. Robinson, of Montreal, Quebec, Canada, for an improvement in "Adjustments for Terminals within Connectors Heads," was erroneously written and printed as "Ellison A. Workman," whereas said name should have been written and printed as *Ellison E. Workman*, as shown by the records of assignments in this office; and that the said Letters Patent should be read with this correction therein that the same may conform to the record of the case in the Patent Office.

Signed and sealed this 16th day of December, A. D. 1924.

[SEAL.]

KARL FENNING,
Acting Commissioner of Patents.
